UNITED STATES PATENT OFFICE

OWEN H. ROBERTS, OF ATLANTA, GEORGIA, ASSIGNOR OF FIFTY-ONE PER CENT TO
ANTHONY PAUL MILLER, OF PLEASANTVILLE, NEW JERSEY

BUILDING CONSTRUCTION

Application filed May 4, 1927. Serial No. 188,693.

The invention relates to walls, partitions, floors and ceilings for residences or other buildings, and also to the various elements of which they may be produced and constructed, which consist of relatively thin slabs of hardened plastic material, as concrete, cement, gypsum, and the like, together with studs and floor beams of similar plastic material.

An object of my invention is to provide a structure which shall be fireproof and weather-proof, and which may be fabricated readily of elements simple of manufacture, and by unskilled labor.

Another object is to provide a structure of the kind described which shall be structurally strong and capable of resisting wind pressure, and which shall be to a considerable extent damp-proof and sound-proof, and resistant to the transfer of heat.

A further object is to provide means whereby walls and partitions of the kind described may readily be erected without the use of external means of temporarily retaining the several elements of which they are composed in order to bring, and retain, them in proper alignment.

Yet another object of the invention is to provide walls and partitions, as well as ceilings, sufficiently straight and true that they may be finished with one coat of stucco or plaster, instead of several as is customary.

Still another object is to provide walls and partitions having one or more sides constructed of slabs which are suitable to receive and hold nails.

With these objects in view and with others which will be apparent in the following description, my invention consists of the various parts and features, and combinations thereof, and the several means of attaining them set forth in the following description and claims, and in the accompanying drawings, which illustrate preferred means of attaining the said objects, it being understood that changes in the precise embodiment of the invention may be made within the scope of the claims without departing from the spirit of the invention.

In the drawings, Figure 1 is a perspective

view of a wall in process of construction, according to my invention.

Figure 2 is an enlarged fragment of a portion of the wall shown in Figure 1, illustrating the joints between two adjacent slabs on each side of the wall, together with the wall stud.

Figure 3 is the same fragment shown in Figure 2, illustrating the clamps and aligning means, also the form for casting stud-
60

Figure 4 is an enlarged fragment showing the abutting ends of two slabs, and illustrating the preferred contour of the edges, and the means of attaching the slabs to the studs. 65

Figure 5 is a vertical section through the wall, as on line 101—101, Figure 1.

Figure 6 is a vertical section on line 102, Figure 5, and illustrates forms for the studs, and means of retaining same.

Figure 7 is an enlarged fragment at 103, Figure 6.

Figure 8 is a vertical section through the wall, showing the sill and header for a window or door opening.

Figure 9 is a vertical section through the wall and floor, showing wall construction, as well as ceiling slabs and floor and spandrel beams.

Figure 10 is a section on line 104—104, so Figure 9.

Figure 11 is a section on line 105—105, Figure 9, showing ceiling slabs, floor beams and means of forming same, floor fill and finish floor.

Figure 12 is a perspective view showing wall slabs and studs, ceiling slabs and floor beams, spandrel beams, floor fill and finish floor.

Figure 13 is a perspective view of a slab 90 either for walls or for ceilings, together with the form or mould in which it may be cast.

Figure 14 is a fragmentary horizontal section on line 106—106, Figure 9, and shows ceiling slabs notched to allow floor beams to 95 bear directly on studs.

Like numbers indicate like parts throughout the several views.

I am aware that various systems of construction have been proposed wherein slabs 100

of plastic material are utilized for the construction of walls and ceilings, and Letters Patent have been granted for certain of such systems. Entirely novel features, however, will be pointed out, whereby such slabs are used with a minimum of labor and falsework. It will also be shown that great accuracy in the manufacture of the slabs is not required, there being no interlocking or interfitting joints or connections. Attention will be called, however, to the desirability of manufacturing the slabs with the exposed face thereof in an approximately true plane.

In the several figures, the numeral 1 indicates the exterior side of the wall, and 2 the interior side thereof. The outer slabs 3 and the inner slabs 4 are placed on edge, in substantially horizontal courses, with the ends abutting. The exterior slabs 3 may be identical with the interior slabs 4 in form, thickness and composition, or the thickness and size may be varied as conditions require; and in certain cases it will be preferable to manufacture the slabs for one or both sides 25 of the wall of a composition wherein cinders, fibre, or the like, is used as the aggregate or a part thereof in order that the slabs may readily receive and hold nails. The slabs are cast or moulded and allowed to attain a certain degree of hardness before being erected.

The slabs having been prepared and cured as aforesaid; a suitable foundation or footing, 5, is laid, and rods, bars or shapes, 6, are inserted into it at intervals to coincide with the vertical joints, 7, between the slabs, which joints, it will be observed, are opposite each other on the two sides of the wall. Pairs, or even more, of such rods or shapes will ordinarily be preferred at each joint, but the system may be carried out with one such member at each joint.

Footing 5 and the rods or shapes 6 having been prepared; a course of slabs 3 on the outer side of the wall are then laid in end-to-end relation, as shown in Figure 1, with the ends abutting, these slabs being temporarily secured to the outer bar 6 by means of the adjustable clamp 9, an enlarged view of which is shown in Figure 3, which simultaneously 45 grips the rod 6 and the adjacent slabs 3 near the ends of the latter, adjustable means being provided in the nuts and washers 10 whereby the distance of the slab from the rod may be fixed as desired and the slab held securely at the fixed distance. A course of inner slabs 4 is then set up opposed to, and spaced from, the slabs 3, and attached temporarily to slabs 3 by means of the bolts 11, the distance between the outer and inner slabs being adjusted by means of the nuts and washers 12, 13, 14 and 15. It will be perceived that no special holes, notches or recesses are required for either the clamps 9 or the clamps 11, but that they are merely laid on the top edges of the slabs. It will also be perceived that in the

manner described both the inner and the outer course of slabs will be held securely in position until the studs, which will be described presently, are poured, when the slabs will be held permanently in place.

It is of course understood that the form of the clamps used may be varied, it being only required that they accomplish the purpose desired and described.

Metal clips, wires, or nails, or the like, as indicated by the numeral 16, Figures 1 and 6, having been inserted in the footing 5 while the latter is yet plastic, spaced at the proper distance from the rods 6, forms 17, 17, which may be of wood or other suitable material, are inserted on either side of rods 6 against clips 16 and clamps 11, hooks 49, Figure 1, preferably being driven into the forms 17 for temporarily holding them in place, said hooks engaging clamps 11. The space between the forms is then filled with plastic material, such as concrete, constituting the stud 18, whereupon clips 20, Figures 6 and 7, the purpose of which will be described presently, are inserted in the top of the plastic stud at either side 90 thereof.

It is to be understood that reinforcing means, 19, such as wires or rods, are embedded in the slabs 3 and 4 and allowed to project from the ends thereof. These rods or wires are bent into the space to be occupied by the stud, so that when the plastic material of which the stud is composed is poured they will be embedded therein, thus firmly and permanently holding the slabs in place.

It is to be especially noted that the reinforcement 19 projects from the ends of the slabs, as is clearly shown in the several figures, thus greatly simplifying the casting of the slabs, as is especially shown in Figure 13.

It will be perceived from the foregoing description that a course of slabs may in the manner described be laid to a line, straight, true and plumb, without the use of falsework or bracing of any kind.

When the plastic material has been poured between the forms 17 and allowed to attain a proper degree of hardness the clamps 9 and 11 and the forms 17 are removed, and a second course of slabs 3 and 4 are erected in the manner already described, and as illustrated in Figures 1, 5 and 6, and the clamps are applied and the slabs aligned as already explained; the metal clips 20 having been bent over at substantially right angles to their original position, as shown at 20a, in Figure 7, ready to receive and retain the lower ends of the stud forms 17, as is clearly shown in Figures 6 and 7. The forms 17 are then inserted and the plastic material poured between them as before.

Figure 1 shows at the left of the figure one course of slabs laid, with the corner stud poured to the height of the first course of slabs, and shows at the first stud from the

corner the clamps 9 and 11 and the clips 16 in place, also the forms 17 ready for pouring the stud. At the right of the figure two courses of slabs are shown in place, with the 5 studs poured and the forms removed. It will be noted that the corner studs are formed and poured in a manner similar to that of forming and pouring the stud already described.

Referring to Figure 13, it will be noted 10 that the slabs are preferably poured flat, with the side which is to be exposed when erected in a wall, uppermost. In this manner it will be convenient to adjust the form for the slab with its upper surfaces in a true 15 plane, and the surface of the slab to be exposed may be floated and scratched suitably to receive stucco or plaster. The reinforcing bars 17, which are preferably near the inner side of the slab when erected are inserted 20 through holes drilled in the forms. When the slab has hardened sufficiently the forms may be removed by withdrawing them laterally, leaving the slab on its pallet for further curing. The ceiling slabs, which will be referred to presently, may be manufactured 25 in a similar manner.

The horizontal and vertical edges of the slabs are preferably formed with a rebate, 22, 30 on the outer side, as shown in Figures 1, 2, 4, 5 and 13, and with a chamfer, 23, on the vertical edges adjacent to inner side, as shown. Thus on the exterior faces of the wall a groove is provided at the horizontal and vertical joints, into which the material of the 35 stucco or plaster, 25, may enter, thus automatically pointing the joints, and providing an unbroken surface on the stucco or plaster. In the case of the inner chamfer, 23, the plastic material of the studs may enter the V- 40 shaped groove thus formed at the vertical joints, and the reinforcing bars 19 are preferably brought out of the slab at this chamfer, as shown in Figures 4 and 13.

I prefer to coat the inner surface of the 45 outer slabs 3 near the ends thereof where the said surface abuts the studs with a coating of pitch, asphalt, or other waterproof material to prevent moisture from passing through the slab into the stud and so to the 50 interior of the building. This waterproofing is clearly shown in Figure 2. I also prefer to coat the unrebated part of the horizontal edges of the slabs 3 with a similar waterproofing material to prevent moisture from 55 entering through the stucco or plaster into the space between the outer and inner course of slabs. This is clearly shown at 27, Figure 9.

Figure 8 shows the manner in which an 60 opening for a window or door may be formed, a stud 18 being carried up on either side of the opening, and a form 45 placed between the slabs 3 and 4 from stud to stud and a plastic sill, 47, poured in the space so formed; 65 and a form, 46, may be similarly placed at

the top of the opening and the header, 48, 70 poured between the slabs 3 and 4. The form 45 would remain in place, and the form 46 be removed.

The construction of the floor system is 75 clearly shown in Figures 9, 10, 11 and 12. When the walls have been built up to the height of the proposed level of the top of the floor beams, in the case of the outer slabs, as at 28, Figure 9, and to the ceiling level in the case of the inner slabs and the studs, as at 29, Figure 9, ceiling slabs, 30, are laid on a falsework, 31, supported on temporary uprights, 32, these slabs being laid with the sides and ends, respectively, of the adjacent slabs abutting, as shown, so as to form a continuous surface for the ceiling. The ceiling slabs are cast or moulded in a manner similar to that already described, as shown in Figure 13, and preferably with the chamfered and 80 rebated edges already described in the case of wall slabs, and with reinforcing members, 34, projecting from two opposite edges, which edges are laid at the lines to be coved later by the floor beams, 33, to be described later. 85 The reinforcing members are bent upward at substantially right angles to the plane of the slabs into the space to be occupied by the beams 33. The ceiling slabs are preferably manufactured with the lower face, or surface, 90 in a substantially true plane, but great care in forming the other face, or the edges, of the slabs is not necessary, as there are no interlocking or interfitting parts. At the walls the ceiling slabs are preferably allowed to 95 extend across the top of the inner slabs, 4, of the walls, to the inner face of the outer wall slabs, 3, as at 35, Figures 9 and 12, to receive the spandrel beam, 36, which will be 100 described later.

The ceiling slabs having been thus prepared and laid, temporary forms, 37, which may be of wood, or other suitable material, are placed on top of the ceiling slabs 30, and 105 temporarily braced and stayed by tie members, 38, as shown in Figures 11 and 12. Reinforcing members, 40, are placed in the beam forms and the space between the forms filled with plastic material, such as concrete. The 110 beams may be constructed with flanges at the upper edges thereof, forming a T-section, as shown, if required for proper strength. Similar forms, 39, Fig. 12 are placed on the top of the slabs near the outer wall slabs and 115 substantially parallel thereto, for the spandrel beams, 36, which are preferably poured monolithically with the floor beams, 33. When the beams have cured sufficiently, the forms 34 and 39, together with the stays, 38, may be 120 removed, and when the beams have attained sufficient strength the falsework 31 and 32 may be removed, and a coat of plaster, 25, 125 may be applied to the under surface of the slabs, 30.

When the forms 34 and 39 have been re- 130

5 moved the space between the beams is filled with any desired material, but preferably with a light, non-combustible substance, such as cinders, or broken brick or tile, and the like. This filling, shown at 44, Figure 12, may be compacted as desired, after which sleepers, or nailing strips, 41, are laid and the space between them filled with cinder concrete, 42, Figures 9 and 12, in the well-known manner, and the finish floor, 43, applied; or, a finish floor of cement or other composition may be laid directly on the fill 44.

10 Figure 14 is a horizontal section of line 15 106—106, Figure 9, and shows the ceiling slabs, 30, with their corners notched out at the stud, 18, so that the plastic material of the beam, 33, when poured, will bear directly on the top of the stud. This construction is 20 also illustrated in the sectional elevation shown in Figure 10.

25 It will be perceived from the foregoing description that a floor system at once strong, fireproof, sound-proof and durable, is produced, with no combustible material as a permanent part of the structure. It will also be noted that the ceiling slabs provide a bottom form for the floor beams and spandrel beams, and that the fill between the 30 beams supports that part of the finish floor which does not rest directly on the floor beams. The rebates form grooves at all joints between the slabs, which grooves are automatically pointed when the plaster is 35 applied. The floor beams are framed monolithically into the spandrel beams, and the floor beams intermediate of the wall studs are supported at their ends by the spandrel beams. It will also be noted that the chamfers at the ends of the ceiling slabs form 40 grooves on the upper face of the slabs into which the plastic material of the floor beams may flow.

Having described my invention, what I 45 claim as new and useful, and desire to secure by Letters Patent is:

1. A building construction of the character described consisting of two sets of plastic slabs spaced apart, each of said sets composed of a plurality of plastic slabs disposed in juxtaposed end to end relation in substantially horizontal courses; reinforcing members longitudinally extending through said slabs and projecting from the ends 50 thereof, said projecting reinforcing members bent at an angle to the plane of said slabs into the space between the two sets of slabs; and plastic studdings, positioned between said spaced slabs and embedding the 55 projecting ends of said reinforcing members.

2. A building construction of the character described consisting of two sets of plastic slabs spaced apart, each of said sets composed of a plurality of plastic slabs dis-

posed in juxtaposed end to end relation in superimposed horizontal courses, the vertical joints of each course of slabs being directly over those of the course below, the vertical joints of one set of slabs being opposite those of the other set of slabs; reinforcing members extending through said slabs and projecting upon the ends thereof, said projecting ends of the reinforcing members being bent at an angle to the plane of the slabs into the space between the two sets of slabs; a foundation supporting said slabs; spaced vertically disposed metallic members embedded in said foundation opposite each of the vertical joints between said slabs and rising in the space between the sets of slabs; studdings positioned between said spaced sets of slabs and embedding said vertically disposed metallic members and the projecting ends of the slab reinforcing members; and, waterproofing means on the inner face of one of the sets of slabs adjacent the ends thereof between said slabs and the studdings.

3. A building construction of the character described consisting of two sets of plastic slabs spaced apart, each of said sets composed of a plurality of plastic slabs disposed in juxtaposed end to end relation in substantially horizontal courses; means for retaining said sets of slabs in spaced relation, bevelled chamfers at the ends of said slabs adjacent the inner faces thereof, reinforcing members longitudinally extending through said slabs and projecting from the ends thereof through said bevelled chamfers, said projecting ends of the reinforcing members being bent at an angle to the plane of said slabs into the space between said sets of slabs and in engagement with the means for retaining the slabs in spaced relation.

4. A building construction of the character described consisting of two sets of plastic slabs spaced apart, each of said sets composed of a plurality of plastic slabs disposed in juxtaposed end to end relation in substantially horizontal courses, plastic studding positioned between the slabs adjacent the meeting ends thereof, studdings retaining the sets of slabs in spaced relation, and waterproofing means on the inner face of one of said sets of slabs adjacent the end of said slabs between said slabs and the plastic studdings.

5. A building construction consisting of a plurality of plastic slabs disposed in juxtaposed end to end relation in successively contiguous rows to constitute a continuous ceiling, the ends of the adjacent slabs of the several rows each lying in a straight line, reinforcing members longitudinally extending through said slabs, projecting from the ends thereof and bent at an angle to retain said slabs, a pair of spaced forms supported on said slabs at each row of the slab ends

extending from one side of the structure to the opposite side thereof and embracing said bent-up ends of said slab retaining members, reinforced plastic material positioned on said 5 slabs between said pairs of forms to constitute beams and embedding said bent-up ends of the slab reinforcing members, and means for supporting each end of each of said beams.

6. A building construction consisting in 10 combination, of a plurality of plastic slabs disposed in juxtaposed relation to constitute a continuous ceiling, a plurality of spaced reinforced plastic beams disposed above and supporting said slabs, means of attaching 15 said slabs to said beams, means of supporting the ends of each of said beams, a filling of inert material supported on said slabs between said beams, and a finish floor applied to and supported upon the tops of said beams 20 and on said inert filling material.

7. A building construction comprising a plurality of plastic slabs disposed in abutting end to end relation, rods positioned in 25 said slabs and extending throughout the length thereof, the extremities of said rods projecting from the opposite ends of said slabs, a studding positioned adjacent the meeting ends of said slabs, and said projecting extremities of the rods being anchored 30 within said studding.

8. A building construction comprising spaced walls formed of plastic slabs, the vertical ends of said slabs being in abutting engagement, plastic columns disposed between 35 said walls, horizontally disposed reinforcing rods positioned in said slabs and extending throughout the length thereof, the opposite ends of said reinforcing rods projecting inwardly at right angles from the slabs at 40 points from their vertical ends, the inwardly extending portions of said rods being embedded in said plastic columns, vertically disposed reinforcing rods arranged within said columns and said right angular inwardly 45 extending portions of said rods being embedded within the columns at the opposite sides of said vertically disposed reinforcing rods.

OWEN H. ROBERTS.
